SPORTSMAN'S LUNCH TOTE SEAT

Henry M. Madden, Detroit, Mich.

Application August 20, 1957, Serial No. 679,302

3 Claims. (Cl. 155—150)

This invention relates to a device which can be used as a sportsman's seat, and wherein the device can also be used for carrying articles such as foodstuff therein.

The object of the invention is to provide a device which can be used at times for carrying various articles such as foodstuffs, such as lunch as well as a Thermos bottle or container, and wherein when desired, the foodstuff and Thermos container can be removed so that the device can be opened up to permit it being used as a convenient seat.

Another object of the invention is to provide a device which is adapted to be used by sportsmen, hunters or the like or by any other individual who finds it convenient, the device being adapted to be arranged in two different positions, and wherein in one position the device is adapted to be used as a convenient seat by an individual, and wherein in another position the seat can be folded so that it provides a convenient means of carrying various articles such as a Thermos bottle as well as foodstuff such as a person's lunch or the like.

A further object of the invention is to provide a sportsman's lunch tote seat which is extremely simple and inexpensive to manufacture.

Other objects and advantages will be apparent during the course of the following description.

In the accompanying drawings, forming a part of this application, and in which like numerals are used to designate like parts throughout the same:

Figure 1 is an elevational view illustrating the device being used for carrying a Thermos bottle and wherein a lunch can be positioned below the Thermos bottle.

Figure 2 is a view showing the parts in the position of Figure 1, and the view in Figure 2 being taken at right angles to the view shown in Figure 1.

Figure 3 is a sectional view taken on the line 3—3 of Figure 1.

Figure 4 is a view similar to Figure 1, but showing the device in opened position as when it is being used as a seat.

Figure 5 is a sectional view taken on the line 5—5 of Figure 4.

Figure 6 is a perspective view showing the device open as when it is to be used as a seat.

Figure 7 is a perspective view of the base for use when the parts are in the position of Figures 1 and 2, wherein the base of Figure 7 can be used for holding a lunch or the like.

Referring in detail to the drawings, the device of the present invention is indicated generally by the numeral 10, and the device 10 includes a pair of open rectangular support members or frame pieces which are each indicated generally by the numeral 11. Each of the support members 11 have the same construction, and each includes a lower first portion 12, and a pair of spaced parallel side portions 13. Extending between the upper ends of the portions 13 and secured thereto or formed integral therewith is a third or upper portion 14. A plurality of straps 15 extend between the upper portion 14 and the

2

straps 15 are connected thereto. When the device is in the position shown in Figures 4 and 6, for example, the straps 15 provide a seat for a person, and when the device is folded as shown in Figure 1 for example, the straps 15 provide a convenient means for carrying the device from place to place.

There is further provided a body member which is indicated generally by the numeral 16, and the body member 16 includes a pair of vertically disposed spaced parallel side walls 17 and an end wall 18. Each of the side walls 17 terminates in a curved section 19, and extending from each curved section 19 is a flange 20 for a purpose to be later described. Pivot pins 21 serve to connect the portions 13 of the support members to the side walls 17 of the body member 16.

When the device is being used for carrying articles, the base 22 shown in Figure 7 is used, and the base 22 includes a horizontally disposed bottom member 23 and a pair of upstanding side members 24 which are arranged in spaced parallel relation with respect to each other. Extending inwardly from the upper edge of each of the members 24 is a lip 25, and the lips 25 are arranged in opposed relation with respect to each other. Each of the lips 25 is provided with an arcuate or curved recess 26 for engaging the lower end of a Thermos container or bottle 27, Figure 1. The flanges 20 of the body member 16 are adapted to frictionally engage the sides of the Thermos bottle 27 so as to help retain the Thermos bottle 27 in its proper position.

From the foregoing, it is apparent that there has been provided a device which in one position can be used as a convenient seat by sportsmen, hunters, or the like, and in Figures 4 and 6 the device is shown in position ready to be used as a seat. Thus, as shown in Figures

35 4 and 6, the pair of support members 11 are arranged in crisscross relation with respect to each other, and the body member 16 is shaped and arranged so that when the support members 11 are in opened position or in crisscross relationship as shown in Figures 4 and 6, the

40 end member 18 and the sections 19 will act as stop members so as to maintain the support members in their proper positions when a person is resting on the straps 15. When the device is not being used as a seat, it can be used as a convenient means of carrying various types of articles.

45 For example as shown in Figure 1, when the device is not being used as a seat the support members 11 can be folded together from the position shown in Figures 4 and 6 to the position shown in Figures 1, 2 and 3 and the base 22 can be supported at the bottom of the device on the portions

50 12. The base 22 is adapted to hold different types of articles such as a person's lunch, and the base 22 is shaped so that it includes the upper lips 25 which are provided with the curved recesses 26 for snugly receiving therein the lower end of a Thermos bottle 27. The Thermos

55 bottle 27 is adapted to project through the body member 16, and the flanges 20 are adapted to frictionally engage the sides of the Thermos bottle 27 so as to help maintain the Thermos bottle 27 in its proper position. Furthermore, when the parts are in the position shown in Figure 60 1 for example, the straps 15 can be conveniently gripped so as to provide a means for readily carrying the device from place to place.

The parts can be made of any suitable material and in different shapes or sizes.

65 Thus, it will be seen that there has been provided a combination lunch box and seat which can be used wherever convenient such as by persons hunting deer, ducks, squirrels and the like, and the device is also adapted to be used by fishermen or by people who like to sit out-of-doors at different locations for long periods of time. The device is compact so that it can be conveniently

used by hikers, persons on picnics and the like, and it can also be used as an extra seat at a cottage, or in the basement. When the seat is folded, it will conveniently accommodate a vacuum bottle such as a one quart size vacuum bottle and a large lunch can also be accommodated therein, and the straps 15 can be swung over the user's shoulder when the device is being carried.

In use, a filled or partially filled lunch box is adapted to be snapped into position in the base 22, and the recesses 26 are snapped into engagement with a vacuum bottle such as a vacuum bottle of one quart size. The bottle and base 22 which contains the lunch are then inserted into the open end of the seat through the body member 16 and the flanges 20 supply sufficient pressure against the bottle to insure that the bottle remains in its proper position. Then, the straps 15 can be placed over the user's shoulder so that the compact unit can be carried to the desired location. When the desired location is reached, the person removes the straps from the shoulder and then the vacuum bottle 27 with the lunch box or base 22 attached thereto can be readily removed from the device. Then, the seat is unfolded by spreading the support members 11 apart so that the carrying straps 15 now becomes the top of the seat. As previously stated, the straps 15 serve the dual purpose of functioning as a carrying strap when the device is being carried, and they also form the seat when the device is being used to sit on. If desired, the device may be carried by hand without utilizing the straps for this purpose. Furthermore, an important advantage of the present invention is that the Thermos bottle will be protected against breakage when it is being transported as for example, when the device is being transported in a vehicle, or when it is being transported or carried by a person or individual and this protection is afforded by the frame of the device for the Thermos bottle or container.

The above description of the invention is for illustrative purposes only and it is understood that modifications may be made in the construction within the scope and spirit of the following claims.

I claim:

1. In a sportman's lunch tote seat, a pair of similar support members of open rectangular formation, each of said support members including a lower first portion, a pair of spaced parallel side portions extending from said first portion, an upper third portion extending between the upper ends of said parallel side portions, said third portion being arranged in spaced parallel relation with respect to said first portion, a plurality of straps extending between the upper third portions and connected thereto, a body member including a vertically disposed end wall and a pair of spaced parallel vertically disposed side walls extending from said end wall, pins pivotally connecting the side portions of said support members to the side walls of said body member, a pair of flanges on said body member, and said flanges being arranged adjacent the inner surfaces of said support members, and a base releasably positioned in the lower portions of said support members.

2. In a sportsman's lunch tote seat, a pair of similar support members of open rectangular formation, each of said support members including a lower first portion, a pair of spaced parallel side portions extending from said first portion, an upper third portion extending between the upper ends of said parallel side portions, said third portion being arranged in spaced parallel relation with respect to said first portion, a plurality of straps extending between the upper third portions and connected thereto, a body member including a vertically disposed end wall and a pair of spaced parallel vertically disposed side walls extending from said end wall, pins pivotally connecting the side portions of said support members to the side walls of said body member, a pair of flanges on said body member, and said flanges being arranged adjacent the inner surfaces of said support members, and a base releasably positioned in the lower portions of said support members, said base including a horizontally disposed body member, a pair of spaced parallel side members extending upwardly from said body member, a lip extending inwardly from the upper edge of each of said side member, said lips being provided with arcuate recesses for engagement with the lower end of a Thermos container.

3. In a sportsman's lunch tote seat, a pair of similar support members of open rectangular formation, each of said support members including a lower first portion, a pair of spaced parallel side portions extending from said first portion, an upper third portion extending between the upper ends of said parallel side portions, said third portion being arranged in spaced parallel relation with respect to said first portion, a plurality of straps extending between the upper third portions and connected thereto, a body member including a vertically disposed end wall and a pair of spaced parallel vertically disposed side walls extending from said end wall, pins pivotally connecting the side portions of said support members to the side walls of said body member, a pair of flanges on said body member, and said flanges being arranged adjacent the inner surfaces of said support members, a base releasably positioned in the lower portions of said support members, said base including a horizontally disposed body member, a pair of spaced parallel side members extending upwardly from said body member, a lip extending inwardly from the upper edge of each of said side member, said lips being provided with arcuate recesses for engagement with the lower end of a Thermos container, said base adapted to hold articles such as foodstuffs therein, the flanges of said body member adapted to frictionally engage the sides of the Thermos container.
